(57) **CLAIM**

The ornamental design for a golf club lamp, as shown and described.

DESCRIPTION

FIG. 1 is a top perspective view of a golf club lamp showing my new design;

FIG. 2 is a front elevation view thereof;

FIG. 3 is a top plan view thereof;

FIG. 4 is a side elevation view thereof;

FIG. 5 is a side elevation view thereof, showing the side opposite from that shown in FIG. 4;

FIG. 6 is a rear elevation view thereof;

FIG. 7 is a top perspective view of a second embodiment of a golf club lamp showing my new design;

FIG. 8 is a front elevation view thereof;

FIG. 9 is a top plan view thereof;

FIG. 10 is a side elevation view thereof;

FIG. 11 is a side elevation view thereof showing the side opposite from that shown in FIG. 10; and,

FIG. 12 is a rear elevation view thereof.

The subject matter shown in broken lines is for illustrative purposes only and forms no part of the claimed design.
